(57) **CLAIM**

The ornamental design for a common mode choke coil, as shown and described.

DESCRIPTION

FIG. 1 is a front view of a common mode choke coil, showing our new design;

FIG. 2 is a rear view of the common mode choke coil shown in FIG. 1;

FIG. 3 is a right side view of the common mode choke coil shown in FIG. 1;

FIG. 4 is a left side view of the common mode choke coil shown in FIG. 1;

FIG. 5 is a top view of the common mode choke coil shown in FIG. 1;

FIG. 6 is a bottom view of the common mode choke coil shown in FIG. 1; and,

FIG. 7 is a perspective view of the common mode choke coil shown in FIG. 1.

The broken lines in the figures depict portions of the common mode choke coil that form no part of the claimed design.
